CLAIM

The ornamental design for a vegetable chopper as shown and described.

DESCRIPTION

FIG. 1 is a top perspective view showing my new design; FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another perspective view shown in opened position thereof; and,

FIG. 10 is a top perspective view thereof.

The broken lines in the drawings depict portions of the vegetable chopper and form no part of the claimed design.

1 Claim, 10 Drawing Sheets(56)
